DENTAL FORCEPS

Filed May 17, 1928

FIG. 1.

FIG. 2.

FIG. 3.

FIG. 4.

George P. Roberts.
INVENTOR.

BY *Master and Attorney*
ATTORNEYS.

UNITED STATES PATENT OFFICE

GEORGE P. ROBERTS, OF TARPON SPRINGS, FLORIDA

DENTAL FORCEPS

Application filed May 17, 1928. Serial No. 278,536.

This invention relates to improvements in dental forceps, pliers, tweezers, and the like, whereby to guard the hand of the user.

The primary object of this invention is 5 the provision of a guard applied to a handle of dental forceps, constituting a support or rest for the thumb of the user, in such a relation that during a tooth extracting operation, if the jaws of the forceps should slip from 10 the tooth of the patient, the dentist's thumb will not be caught between the handles.

Other objects and advantages of this invention will be apparent during the course of the following detailed description.

15 In the drawing, wherein for the purpose of illustration is shown only a preferred embodiment of this invention,

Figure 1 is a top plan view of the forceps, showing in dotted lines the relation of the 20 operator's hand thereto.

Figure 2 is a perspective view of the forceps, showing the guard applied thereto.

Figure 3 is a transverse sectional view 25 taken through the forceps at the location of the guard.

Figure 4 is a developed view of the guard prior to appliance to the forceps.

In the drawing, wherein similar reference characters designate corresponding parts 30 throughout the several views, the latter A may generally designate the improved forceps, with which the guard B may be associated in an integral, or otherwise affixed relation.

35 Dental forceps, as well known to those skilled in the dental art, comprises a pair of members 10 and 11, pivoted together at some location 12 intermediate their ends, and so that the members 10 and 11 respectively provide jaws 13 and 14, and handle portions 15 and 16. It is well known that considerable force is applied to the forceps during a tooth extracting operation, and in the case of pliers, force is exerted during an operation.

40 If the jaws 13 and 14 should slip from the object being grasped, it is very likely that the thumb of the operator will be caught between the handle portions 15 and 16 adjacent the pivot. To obviate this I provide the 45 guard member B, which may be applied to

one of the handles adjacent the pivot, in such relation that it will form a shelf or support overlying and overlapping the other handle when the jaws of the forceps are in clamping position.

55 As a preferred means of securing the guard member B in place, I use a flat piece of material, such as shown in Figure 4, preferably metal of any approved nature, although it may be of other material if found practical. 60 It consists of an elongated attaching portion 20, having an enlarged wider shelf portion 21 at an end thereof, forming a surface suitable for supporting the thumb of the operator. As to its application upon the handle 15, I prefer to recess the handle at 23 inwardly from the top thereof at the side opposite the side from which the jaws laterally extend, as shown in Figure 3 of the drawing. The recess 23 is continued in the material 65 at the sides of the recess, to provide flanges 27 with recesses extending therebeneath, and into which recess, and beneath said flanges 70 the guard B may be forced.

Inasmuch as the guard member B in its developed form shown in Figure 4 is wider at its shelf end, it is readily apparent that the attaching end may be slipped laterally into place in the recess 23 beneath the flanges 27, and held tightly in this position, and the attaching end 20 may be rolled, as shown at 25 in Figure 3 of the drawing, about the exterior side of the handle 15 transversely thereacross, and bent as shown at 26 against the inside thereof. The intermediate portion of the 75 guard B is dished downwardly at 27^a, between the handles 15 and 16, and the shelf or support 21 extends upwardly and in a relation to overlap the handle 16 when the plier handles are in operating relation, as shown in 80 Figures 1 and 3 of the drawing.

85 It is quite apparent from the foregoing that during an operation the operator grasps the handles of the pliers or forceps between the hands, with the thumb resting on the support 21 of the guard B. The handles are brought together and when the jaws grasp the object to be clamped, the handle 16 is already beneath the support portion 21, so 90 that there is no liability of pinching the op- 100

operator's thumb if the jaws should slip from the object being grasped and should come together sharply.

Various changes in the shape, size, and arrangement of parts may be made to the form of invention herein shown and described, without departing from the spirit of the invention or the scope of the claims.

I claim:

- 10 1. In dental forceps a pair of pivoted members, each member including a jaw portion and a handle portion, and a thumb engaging guard member rigidly connected with one of the handle portions and constituting a laterally extending thumb support free of the other handle but in position to substantially overlie the adjacent portion of the said other handle portion in position where the operator naturally grasps the same when the members are in an operating position.
- 15 2. In forceps the combination of a pair of pivoted members each including a jaw portion and a handle portion, the jaws extending laterally from the plane in which the members lie, and a rigid thumb support and guard member connected with one of the handle portions and extending laterally to overlap the other handle portion adjacent the pivot of said members and at the opposite side at the plane of said members from the side to which the jaws extend.
- 20 3. In dental forceps the combination of a pair of pivoted members each including a jaw portion and a handle portion, and a thumb support secured rigidly to one member at a location where an operator places his thumb for a normal grasp of the device and extending laterally in an overlying relation with the other member but free of connection therewith to permit relative pivoted movement of said members in an unimpeded relation and the application of pressure thru the thumb of the operator on said support.
- 25 4. In a device of the class described the combination of a pair of pivoted members each including a jaw portion and a handle portion, and a thumb guard wound about and rigidly secured to one of the pivoted members and extending laterally at an end thereof in an overlying thumb protecting relation with respect to the other member.
- 30 5. In a device of the class described a pair of pivoted members each including a jaw portion and a handle portion, one of the handle portions being recessed, and a guard member rigidly seated in said recess and extending about said handle portion and at an end thereof laterally extending into an overlying relation with respect to the handle portion of the other pivoted member.

GEORGE P. ROBERTS.
